US00D522499S

(12) **United States Design Patent** (10) Patent No.: **US D522,499 S**
(45) Date of Patent: **** Jun. 6, 2006**

(54) **MICROPHONE SENSOR**

(75) Inventors: **Martin E. Marcichow**, Hoffman Estates, IL (US); **Gregory C. Perna**, Las Vegas, NV (US)

(73) Assignees: **Sloan Valve Company**, Franklin Park, IL (US); **Wynn Design & Development LLC**, Las Vegas, NV (US)

(**) Term: **14 Years**

(21) Appl. No.: **29/221,060**

(22) Filed: **Jan. 11, 2005**

(51) LOC (8) Cl. **14-01**

(52) U.S. Cl. **D14/225**

(58) **Field of Classification Search** D14/225, D14/226, 227, 228, 188, 192, 155, 240; D9/552, D9/556; D10/104; 359/504; 181/158, 242; 381/111, 122, 174, 355, 369; D99/5; 27/1; D16/130, 134, 136; 251/129.04; 250/221; 4/623

See application file for complete search history.

(57) **CLAIM**

The ornamental design for a microphone sensor, as shown and described.

DESCRIPTION

FIG. 1 is a perspective view of our new design for a microphone sensor;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are for illustrative purposes only and forms no part of the claimed design.
